(57) **CLAIM**

The ornamental design for a reactor vessel radiation shielding, substantially as shown and described.

DESCRIPTION

FIG. 1 is a front perspective view of a reactor vessel radiation shielding showing the new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The particular length and dimensions of the shielding depicted in the figures form no part of the claimed design, as no particular length and/or dimension is claimed.

The broken lines shown represent unclaimed subject matter and form no part of the claimed design.
